UNITED STATES PATENT OFFICE.

WEB M. EDDINS, OF BARNETT, MISSISSIPPI.

COMBINATION TRIMMING SAW AND SLAB KICKER.

Application filed April 28, 1926. Serial No. 105,241.

The object of the invention is to provide a mechanism for use particularly with portable saw mills, so that the trimming of lumber may be readily accomplished and the resultant waste slabs promptly disposed of with a minimum of work on the part of the operator; to provide a construction wherein the kicker drum is directly coupled to the trimming saw to rotate the latter and also to feed the latter to the work; and to provide a construction wherein the feed may be under the control of the operator to effect it and discontinue it when necessary and independent of the rotation of the saw.

With this object in view, the invention consists in a construction and combination of parts of which a preferred embodiment is illustrated in the accompanying drawings, wherein:

Figure 1 is a top plan view of the apparatus embodying the invention.

Figure 2 is a side elevational view, there being indicated in dotted lines a foot control for the feed.

Figure 3 is a longitudinal sectional view on the plane indicated by the line 3—3 of Figure 1.

Figure 4 is a transverse vertical sectional view on the plane indicated by the line 4—4 of Figure 3.

Figure 5 is a detail sectional view on the plane indicated by the line 5—5 of Figure 2.

The trimming saw 10 is rotated on its own axis as well as being fed bodily to the work by means of the shaft 11, the latter carrying the toothed drum 12 designed for the disposition of the waste slabs and being terminally provided with a pulley 14 by means of which it may be belt-driven from an appropriate countershaft. The shaft 11 is journaled, as indicated at 15, in a frame 16, the latter being a lateral extension of the main frame 17 on which the saw frame 18 is slidably mounted, the latter traversing the slides 19 of the main frame and being guided in its movement by the straps 20, the latter straddling the side rails of the saw frame.

The mandrel 21 by which the saw is carried is journaled in the saw frame at the forward end of the latter and between the side rails of the saw frame carries a pulley 22, over which is trained a driving belt 23, the latter also being trained over a pulley 24 carried by the shaft 11 over a tightener pulley 25 and over a rear pulley 26, the lat-

ter being carried on a shaft 27 spanning the side rails of the saw frame and journaled in appropriate bearings formed therein. The tightener pulley 25 is carried by a rock frame 28 pivoted, as at 29, to the main frame and subject to the tension of a contractile spring 30 having one end secured to the rock frame and the other end to the extremity of an eye-bolt 31 mounted in the main frame and provided with an adjusting nut 32 by which the tension of the spring may be regulated and therefore the pull of the tightener pulley. By this construction, motion on its own axis is communicated to the saw from the shaft 11, this shaft being driven by the pulley 14 and hence rotating the kicker drum simultaneously with the saw.

In operation, the saw is advanced bodily in a direction at right angles to its axis of rotation for the trimming of stock carried by the roller bed which is disposed in the position indicated by the dotted line in Figure 1. The saw, therefore, moves transversely across the roller bed over which the lumber moves as in the conventional practice. The rough ends are trimmed by stopping the lumber on the bed and then advancing the saw frame for the trimming of the lumber, the useless slabs being then manually cast onto the kicker drum 12 and, impinging upon the teeth thereof, are cast to a point remote from the apparatus.

The bodily movement of the saw and saw frame is effected by means of the belt 23 which rotates the saw. On the main frame 17, there is mounted a second rock frame 33 pivoted to the main frame, as indicated at 34. This rock frame 33 carries at its upper end a friction roller 35 adapted for movement toward and away from the lower run of the belt 23. On the shaft 36 by which the friction roller 35 is carried, there is mounted a winding drum 37, this drum being carried on the protruding end of the shaft 36 and to it there is connected one terminal of a feed cable 38, the latter traversing the idler sheaves 39 and 40 rotatably mounted on the main frame and disposed respectively adjacent the rear and forward guide straps 20, 105 the feed cable being terminally anchored, as at 41, to one of the side bars of the saw frame. The idler sheaves 39 and 40 are simply direction rolls, so that as the drum 37 is rotated, the cable may be reeled thereon and the saw frame bodily advanced to feed the saw to its work. Whether or not the frame

will be moved depends upon whether the friction roller 35 engages the belt 20 and provision is made for moving it into and out of such engagement, such means comprising, for manual operation, a hand lever 42 pivotally mounted on the main frame, as at 43, and having a pivotal connection 44 with a link 45 which is pivotally connected, as at 46, with the rock frame 33.

10 Obviously, the application of a pull on the upper portion of the hand lever will effect movement of the rock frame to engage the friction roller 35 with the belt 20, and, if the shaft 11 be rotated, the saw frame will 15 be advanced as well as the rotation of the saw 10 effected. Means may be provided for locking the hand lever in the position where the friction roller is engaged with the belt or in the position where the friction roller is 20 disengaged therefrom but in practice this is not found to be necessary or even advisable, the operator merely maintaining his pull on the hand lever during the movement of the saw to its work. When the cut has been con- 25 cluded, the release of pressure on the hand lever will permit the saw frame to be returned to its initial position which is accomplished by means of weights 47 with which cables 48 are connected, the latter being termi- 30 nally secured, as at 49, to the rear end of the saw frame and trained over sheaves 50 rotatably mounted at the rear end of the main frame.

In Figure 2 is illustrated in dotted lines a 35 pedal 51 for effecting the movement of the rock frame 33 to engage the friction roller 35 of the belt 20. This pedal is pivotally mounted, as indicated at 52, and provided with an upturned extension 53, the extremity of which extends through an eye 54 in the forward extremity of the link 45. Obviously, the pressure upon the pedal 51 will 40 serve to effect longitudinal movement of the link in the same manner as is accomplished by the hand lever 42 and therefore constitutes a foot means for the actuation of the saw feed.

The invention having been described, what is claimed as new and useful is:

50 1. Apparatus for the purpose indicated comprising a toothed kicker drum, a bodily movable saw frame, a rotary saw carried at

one extremity of said saw frame, and a common means for rotating the drum, effecting bodily movement of the saw frame and rotating the saw on its own axis.

2. Apparatus for the purpose indicated comprising a frame, a toothed kicker drum rotatably mounted in the frame, a rotary trimming saw having a frame mounted for bodily movement in the main frame, and operative connections between the drum, the saw and the saw frame for effecting rotation of the saw on its own axis from the drum and bodily advancing the saw frame.

65 3. Apparatus for the purpose indicated comprising a sliding saw frame, a rotary saw mounted in said saw frame, a shaft having a pulley disposed below said saw frame, a toothed kicker drum carried on said shaft 70 at one side of the saw frame, pulleys mounted at the remote ends of the saw frame, one of said pulleys being operatively connected with the saw, a belt trained over all of said pulleys, and means for effecting bodily movement of the saw frame, said means being actuated by said belt.

75 4. Apparatus for the purpose indicated, comprising a main frame having a lateral extension, a saw frame slidably mounted on the main frame, a rotary saw having a mandrel rotatably mounted at one end of the saw frame, a pulley carried by said mandrel, a second pulley carried at the remote end of the saw frame, a shaft journaled in the main frame and lateral extension thereof, a toothed kicker drum carried on said shaft and disposed in said lateral extension, a pulley carried by said shaft, a belt trained over all of said pulleys, a friction pulley movable 80 into and out of engagement with said belt and having an operative connection with said saw frame to effect bodily movement of the latter in one direction, gravity actuated means for effecting movement of the saw frame in the opposite direction, said gravity actuated means consisting of weights having flexible members terminally connected with the saw frame, and guides over which said flexible members are trained.

90 95 In testimony whereof he affixes his signature.

WEB M. EDDINS.
